UNITED STATES PATENT OFFICE.

HYMAN ELI GOLDBERG, OF CHICAGO, ILLINOIS, ASSIGNOR TO GOLDBERG CALCULATING MACHINE COMPANY, OF CHICAGO, ILLINOIS.

TABULATING-MACHINE.

1,119,010.

Specification of Letters Patent.

Patented Dec. 1, 1914.

Continuation in part of application Serial No. 563,561, filed May 26, 1910. This application filed August 19, 1911. Serial No. 644,969.

To all whom it may concern:

Be it known that I, HYMAN ELI GOLDBERG, a citizen of the United States, residing at Chicago, in the county of Cook and State 5 of Illinois, have invented a certain new and useful Improvement in Tabulating Machines, of which the following is a specification.

This application is a continuation in part of my application Serial Number 563,561, filed May 26th, 1910.

My invention relates to tabulating mechanism for typewriters and is intended particularly for the easier manipulation of a typewriter in the listing of numbers. It is illustrated by the drawings, whereof—

Figure 1 represents an end elevation of a typewriter of the Remington style and Fig. 2 a front elevation of the same. Fig. 3 represents a detail of the mechanism. Fig. 4 20 is a back elevation of a typewriter of the Remington style as used with my machine.

Mounted on the framework 1 of the typewriter is the carriage 2, which normally is given a tendency to move to the left (as viewed from the front of the machine) by means of the tape 41 attached thereto, which is placed under tension by the ordinary spring barrel 40. The keys of the typewriter are of course present, but as they are not 30 part of my invention they are omitted from the drawings for the greater clarity of the illustrations.

The spacing lever 3, operating the platen 4 of the typewriter, is mounted in the usual manner. The tabulator bar 5 is placed at the back of the carriage, to which it is rigidly fastened, and is operated in conjunction with the tabulator rods 6 in order to stop the carriage at any desired place. These 40 tabulator rods 6 are operated by the tabulator keys 7 and the intermediate links 8. The mechanism is old and therefore will not be further described.

Mounted upon the framework 1 is a tube 45 10 in which there works a piston 11 and piston rod 12. This piston rod is connected to an arm 42 rigidly mounted in the spacing lever 3 above mentioned. At the opposite side of tube 11 is the cock 13. This piston 50 and piston rod are operated by means of compressed air in the well known manner, as, for instance, the manner used in the Main pneumatic carriage return described in Pat-

ent No. 892,068. This pneumatic return also being old will not be further described.

Mounted on the shaft 20, which has bearings in the framework of the typewriter, are a series of arms 21, one for each of the tabulator keys 7. These arms are rigidly fastened to the shaft so that when a tabulator key is depressed it rocks the shaft about its center, putting force into the spring 27. Arm 22 is fastened to the shaft and operates the link 23, which in turn operates the cock 13, above mentioned. Thus the depression 65 of a tabulator key 7 results in the rotation of the rod 20 and this by means of the link 23 opens the cock 13, admitting the compressed air to operate upon the piston 11. This thereupon moves to the right and by 70 means of the piston rod 12 forces the carriage of the typewriter back to the right and simultaneously feeds paper upward since the force applied to said carriage by the piston rod 12 acts on the arm 42 rigid in 75 the spacing lever 3. The carriage moves as far as it can, that is, until it is stopped by the contact of the carriage tabulator stop 9, which is inserted in one of the notches of the tabulator bar 5, striking against the tabulator rod 6 which has been protruded by the motion of the tabulator key 7. As long as key 7 is kept depressed the carriage remains in the same place. Upon the removal of the finger from the tabulator key the 80 carriage is caught and held in the same place that it was brought to by the compressed air.

The method of tabulating a column of figures is as follows: After a number has been 90 printed by the figure keys of the typewriter and a units figure typewritten, the proper tabulator key for locating the first figure of the succeeding number will be pressed. The carriage will thereupon be shifted back to 95 the right to the proper place by the mechanism described, the paper will be fed and everything will be in readiness for the operation of the number keys for the typewriting of the next number. A tabulator 100 key will then again be depressed, locating the carriage for the next number, and so on.

This mechanism differs from the ordinary tabulator mechanism in the fact that while an ordinary tabulator allows the carriage to 105 move to the left and stops it at the desired

place, this mechanism drives the carriage to the right and stops it at the proper place. But in order that this mechanism may not interfere with the ordinary use of the tabulator, it is modified as follows: A lever 30 is mounted upon an arm 31, which is rigidly connected to arm 22, above described. Arms 31 and 22 form one piece, which rotates loosely upon the shaft 20, and arm 32 is rigidly attached to shaft 20 and so located that it is able to act upon the end 33 of the lever 30 when the latter is in the position illustrated in Fig. 1. The depression of a tabulator key therefore rocks the shaft 20, which by means of arm 32, operating upon arm 31, rocks the lever 30 and operates as above described. But should the handle 35 of the lever 30 be pulled forward it will serve to disconnect arm 32 and lever 30 and the operation of any of the tabulator keys will now have no effect upon the pneumatic mechanism and the carriage will therefore move to the left in the ordinary manner. Thus the same set of tabulator keys may be used to locate the carriage of the typewriter allowing it to move to the left in the ordinary manner when the handle 35 is pulled forward, or moving the carriage to the right when the handle 25 is in the position illustrated in Fig. 1.

As far as I am aware, I am the first to construct a typewriter, the carriage of which can have the normal motion to the left for the letter space advance thereof and also have an additional power mechanism to return the carriage to the right, in connection with a tabulator stop adjustable upon the carriage whereby the carriage may be located in any desired position.

I am aware that mechanism has previously been constructed whereby the carriage of a typewriter might be fed either to the right or to the left; but, as far as I know, the return of a carriage to the right and the location thereof at the desired position has always been accomplished by the use of at least two motions of the operator,—one for the determination of the exact point of stopping, the other for the connection of the power mechanism to feed the carriage to the right. In my mechanism the stop is made adjustable, permitting the carriage to be located at any required position, and the mechanism for the returning of the carriage is also set once only and thereafter requires no extra manipulation in order to bring it into operation. The one touch of a proper tabulator key simultaneously brings this power mechanism into operation and protrudes the proper tabulator rod to stop the carriage at a desired point.

Attention is here directed to the fact that the carriage tabulator 9 can be inserted in any one of the notches of said tabulator bar.

The tabulator stop is therefore adjustable

upon the tabulator bar or upon the carriage of the typewriter. Again, while in the drawing the tabulator rods 6 are in the form of long plates they need not be in any such form and can be varied considerably without departing from the spirit of the invention. The illustrations have shown a typewriter of the Remington style, wherein the typewriter basket is stationary while the paper support moves. Of course, in the book typewriters it is the typewriter basket that moves while the paper is stationary. This necessarily compels a change of the coöperating portions and the normal letter space advance of what is now the carriage, that is, the type basket, is to the right and the return, of course, is to the left,—just in the opposite directions from the ones previously described. By the feeding of the carriage I therefore understand the normal motion of the moving part during the typewriting of the words and by the return of the carriage I mean the opposite direction, it being unimportant whether the feeding motion be to the right or to the left.

I claim:

1. In a typewriter, a carriage tending normally to advance, means for returning the carriage in the opposite direction, a tabulator stop mounted upon the typewriter, a set of tabulator rods to coöperate with said tabulator stop, a set of tabulator keys one for each of said tabulator rods, and a handle capable of being set in two positions and operative when in one position to connect the tabulator keys with the carriage returning means and in the other position to disconnect the tabulator keys from the returning means. 95
2. In a typewriter, a carriage, means for returning the carriage to the right, means for stopping the carriage at any predetermined place, and connecting means which may be located in either of two positions, and operative in one position to make a connection between the stopping means and returning means and not so operative when placed in the other position. 105
3. In a typewriter, a carriage, means for returning the carriage to the right, tabulating means including a series of tabulator keys, the operation of any of which determines the place at which the carriage will be stopped, a handle, capable of being placed in either of two positions, and which is operative while in one position to connect the tabulator keys with the returning means and which in the other position is not so operative. 115
4. In a typewriter, a carriage, a cylinder for compressed air for returning said carriage to the right, a cock for admitting the compressed air into the cylinder, a series of tabulator keys, the depression of any of which serves to stop the carriage at a place 125

dependent upon the value of the depressed key, a body operable by each of the keys, and a connection between the universal body and the cock, said connection being placeable in either of two positions, in one of which it serves as a connection between the universal body and the cock, and in the other of which it does not so serve.

5. In a typewriter: a carriage tending normally to advance; means for returning the carriage; mechanism for stopping the carriage at any predetermined place in its advance or its return; and connecting means which may be located in either of two positions, and which is operative in one position to make a connection between the stopping mechanism and the returning means, and not so operative when placed in the other position.

10. In a typewriter: a carriage tending normally to advance; means for returning the carriage in the opposite direction; a tabulator stop mounted upon the typewriter; tabulating means to coöperate with said tabulator stop; and a handle capable of being set in two positions, and which is operative when in one position to connect the tabulating means with the carriage returning means, and when in the other position to disconnect the tabulating means from the returning means.

15. In a typewriter: a carriage tending normally to advance; a cylinder for air at a pressure different than the atmosphere, said air serving to return said carriage; a cock opening the cylinder to the working air; a series of tabulator keys the depression of any of which serves to stop the carriage at a place dependent upon the value of the depressed key; a body operable by each of said keys; and a connection between the body and the cock, said connection being placeable in either of two positions, in one of which it serves as a connection between the body and the cock, and in the other of which it does not so serve.

20. In a typewriter: a carriage tending normally to advance; a cylinder for air at a pressure different than the atmosphere, said air serving to return said carriage; a cock opening the cylinder to the working air; tabulating means, the operation of which serves to stop the carriage at a place determined by the tabulating means; a body operable by said tabulating means; and a connection placeable in either of two positions, in one of which it serves as a connection between the body and the cock, and in the other of which it does not so serve.

25. In a printing tabulating machine, the combination of: printing mechanism; means for advancing the carriage; means for re-

turning the carriage; tabulating mechanism independent of the printing mechanism; and a switch determining when in one position said tabulating mechanism shall control the carriage-advancing means and when in the other position said tabulating mechanism shall control the carriage-returning means.

30. In a printing tabulating machine, the combination of: a set of printing keys; a set of tabulating keys; means for advancing the carriage; means for returning the carriage; and a switch determining when in one position that said tabulating keys shall control the carriage-advancing means and when in the other position that said tabulating keys shall control the carriage-returning means.

35. In a printing tabulating machine, the combination of: printing mechanism; paper-feeding means; tabulating mechanism; and manual means independent of said printing mechanism operative on both the tabulating mechanism and the paper-feeding means.

40. In a printing tabulating machine, the combination of: paper-feeding means; tabulating mechanism; printing keys; and a set of tabulating keys operative on both the tabulating mechanism and the paper-feeding means.

45. In a printing tabulating machine, the combination of: paper-feeding mechanism; means for advancing the carriage; means for returning the carriage; printing keys; and a tabulating mechanism independent of said printing keys operative on said means for advancing the carriage, said means for returning the carriage and said paper-feeding mechanism.

50. In a printing tabulating machine, the combination of: a set of printing keys; a set of tabulating keys; means for advancing the carriage; means for returning the carriage; and paper-feeding mechanism; said tabulating keys being operative both on said carriage-returning means and said paper-feeding mechanism.

55. In a printing tabulating machine, the combination of: a set of printing keys; a set of tabulating keys; means for advancing the carriage; pneumatic means for returning the carriage; and paper-feeding mechanism; said tabulating keys being operative both on said carriage-returning means and said paper-feeding mechanism.

60. In witness whereof, I have hereunto subscribed my name in the presence of two witnesses.

HYMAN ELI GOLDBERG.
